United States Patent Office

Des. 217,640
Patented May 19, 1970

217,640

SCALE

Dieter Rams, Koenigstein, Germany, assignor to Braun
Aktiengesellschaft, Frankfurt, am Main, Germany

Filed Dec. 6, 1968, Ser. No. 14,960

Claims priority, application Germany June 6, 1968

Term of patent 14 years

Int. Cl. D10—99

U.S. Cl. D52—10

Fig. 1

Fig. 2

Fig. 3

FIG. 1 is a perspective view of a scale showing my new design;

FIG. 2 is a top view; and

FIG. 3 is an end view of this scale.

The bottom view of this scale not shown in the drawing is plain.

I claim:

The ornamental design for a scale, substantially as shown and described.
